UNITED STATES PATENT OFFICE.

JOSEPH H. CAMPBELL, OF NEW YORK, N. Y., ASSIGNOR OF THREE-EIGHTHS
TO CHARLES H. CAMPBELL AND JAMES McLAIN, BOTH OF SAME PLACE.

METHOD OF UTILIZING AQUA-AMMONIA AS A MOTIVE POWER IN ENGINES.

SPECIFICATION forming part of Letters Patent No. 337,374, dated March 9, 1886.

Application filed July 27, 1885. Serial No. 172,778. (No specimens.)

To all whom it may concern:

Be it known that I, JOSEPH H. CAMPBELL, a citizen of the United States, residing at New York, in the county of New York and State 5 New York, have invented certain new and useful Improvements in the Methods of Utilizing Aqua-Ammonia Vapor as a Motive Power in Engines, of which the following is a specification, reference being had therein to the accompanying drawing.

My invention relates to improvements in the method of utilizing the vapor of aqua-ammonia as a motive power in engines.

The object of my invention is to maintain a 15 high heat or working temperature within the cylinder of the engine, and also uniting the expanded vapor with the weak solution and cooling the same, that it may be returned by the pump to the boiler.

20 My invention consists in the method hereinafter described of forcing a weak solution of aqua-ammonia into the cylinder of the engine, bringing it in contact with the expanded vapor within the cylinder, thereby condensing or absorbing the expanded vapor, and by the act of absorption restoring to the cylinder the heat abstracted by the vapor in doing work by expansion, in order that there 25 may be no loss of heat from the incoming vapor to heat the cylinder and piston up to the proper working temperature, and in this manner to also disseminate the heat of absorption, and thus cause the cylinder to assist the absorber.

30 In the drawing I have shown in side elevation, partly in section, a reservoir, engine, and cylinder, cooler, absorber, pump, and the necessary connecting-pipes which constitute my device or plant, the boiler being omitted.

40 It may be necessary to state in this connection that the boiler-reservoir and other parts of the engine, except the devices which inject the solution into the cylinder, and the devices which carry off the exhaust, are essentially of the same construction as shown, described, and claimed in an application prepared by me of even date herewith, Serial No. 172,776.

45 As before stated, the boiler is not shown, but it connects with the dynamical reservoir A

by means of the pipes *a b*, the former being 50 for the passage of the solution from the boiler to the reservoir, while the latter is for the passage of the vapor from the upper portion or vapor-space of the boiler to the dynamical reservoir A. The pipe B leads also from the 55 boiler, and conveys the solution by means of coils through the reservoir, where it parts with its heat to superheat the vapor in the reservoir, from whence it passes through the cooler C, and is connected to the cylinder in 60 such a manner as to inject jets or spray of the cold weak solution into the cylinder, as will be more fully hereinafter described.

D is the cylinder, which may be provided with an outside casing, E, so arranged as to 65 leave a space, F, between the cylinder D and outside casing, into which the unabsorbed vapor from the cylinder passes through the pipe G, said pipe being connected to the pipe H, which enters the space F, and into which is 70 sprayed a cold weak solution of aqua-ammonia from the pipe B, which absorbs the vapor coming from the cylinder through the pipe G.

H and I are branch-pipes leading from the pipe B and entering each end of the cylinder, 75 said pipes being provided with valves K and L, connected by a rod, M, and operated by an eccentric, N, and rod O, from the main driving-shaft, in such a manner as to alternately cut off and supply the cold weak solution to 80 each end of the cylinder.

The throttle-valve P being opened, the vapor is admitted from the reservoir A through the pipe R to the cylinder D, which drives the piston forward by full boiler-pressure 85 to the front of "cut-off." The remaining portion or balance of the stroke is effected by expansion. As soon as the piston completes the stroke, and has moved on the return-stroke, the valve L is opened and admits a spray of 90 the cold weak solution from the pipe I. The cold weak solution coming in contact with the cold expanded vapor within the cylinder instantaneously absorbs it, making a partial vacuum on that side of the piston, and heating the 95 piston and working-surface of the cylinder by the heat of absorption to the proper working temperature, so that the vapor which is ad-

mitted to make the return-stroke will not be chilled or its working power impaired. When this heat, either by continuous working or by an excess of the weak solution, is so high as 5 to revaporize any portion of the absorbed vapor, this vapor is drawn off through the pipe G into the pipe H, where it meets with the cold weak solution from the pipe B under boiler-pressure, and is absorbed and forced 10 into the jacketed space F of the cylinder, and passes thence to the absorber S. That portion of the vapor within the cylinder which has been absorbed and held in solution, is driven forward to the end of the cylinder by 15 the piston, and passes out through the pipe or pipes T, said pipes being provided with an ordinary steam-trap, (not shown,) which prevents the vapor from passing out while being used to operate the piston.

20 It will of course be understood that the piston is worked in both directions by the vapor, the valve K being brought into requisition by the return-stroke of the piston.

U is a pipe leading from the upper portion 25 or jacketed space, F, to the absorber S, through which the surplus vapor is conveyed from the space F to the absorber, and by which means any back-pressure on the piston is prevented.

Having thus described my invention, what I claim is—

1. The method herein described of heating the cylinder and piston of a vapor-engine, which consists in bringing a cold weak solution in contact with the cold expanded vapor within the cylinder of the engine, as set forth, 30 whereby the cylinder and piston are heated to the proper working temperature by the heat of absorption.

2. The method herein described of heating the cylinder and piston of a vapor-engine, the 40 same consisting in injecting a cold weak solution of aqua-ammonia alternately at each end of the cylinder, said cold weak solution being delivered under boiler-pressure, as set forth.

3. The method herein described of disseminating the heat of absorption, the same consisting in bringing the liquid and expanded vapor when in the act of solution in contact with the piston and working-surface of the cylinder and imparting its heat thereto.

In testimony whereof I affix my signature in presence of two witnesses.

JOSEPH H. CAMPBELL.
